COMBINED SOLARIUM AND AIRING CABINET

Maud E. Trone, Chicago, Ill.

Application August 18, 1943, Serial No. 499,097

5 Claims. (Cl. 128—372)

This invention relates to improvements in a combined solarium and airing cabinet, especially adapted for babies and small children, and it consists of the matters hereinafter described and more particularly pointed out in the appended claims.

One of the objects of the present invention is to provide a device that may be readily positioned in the lower part of a window opening in a home, to receive a baby either for treating the same to the beneficial rays of the sun or for airing the baby.

Another object of the invention is to provide a device of this kind which may be so positioned in a window opening, as to preclude its accidental falling therefrom but which may be readily removed from the opening when it is so desired.

A further object of the invention is to provide a device of this kind wherein one of the parts thereof may be used as an inner end door for the cabinet or a table-like support upon which the baby may be placed when changing its clothing or otherwise attending the same.

Also, it is an object of the invention to provide a device of this kind wherein ventilation therethrough may be controlled and at the same time prevent the entrance of weather elements or insects so that the baby is fully protected at all times.

Again, it is an object of the invention to provide a device of this kind which is of a simple construction and which may be disassembled by inexperienced persons for storage in a comparatively small space and may also be easily reassembled for use.

The above mentioned objects of the invention, as well as others together with the advantages thereof will more fully appear as the specification proceeds.

In the drawing:

Fig. 1 is a perspective view of the device ready for application in a window opening.

Fig. 2 is a longitudinal vertical sectional view through the same, from its inner end to its outer end, when in position within an associated window opening.

Fig. 3 is a horizontal detail sectional view through one side of the device, on a somewhat enlarged scale, as taken on the line 3—3 of Fig. 2.

In general the improved solarium and baby airing cabinet includes an upright frame adapted to be set in the outer sash grooves of a conventional sliding window frame, when the upper sash is in its normal position. The size of this frame is, of course, decided by the size of the window

opening in which it is to be used. This frame is made to define an opening that may be closed by a bottom hinged door. When the door is in its open horizontal position, it projects into the room of which the window forms a part and there provides a dressing table for use in connection with the cabinet. The cabinet includes a generally hollow, rectangular body which is detachably connected to parts of the frame about the opening therein and such a body includes an imperforate horizontal bottom, upright sides and outer end walls and an inclined top wall. The bottom fits in a horizontal supporting frame which is operatively connected at its inner end to the upright frame and guy members connect the outer end of the horizontal frame to parts of the window casting with which the device is used.

The outer end wall, which is relatively low in height, forms a part of a channel along the outer bottom corner of the body and said wall has air inlet openings therein and the top wall of the channel has upwardly opening outlet openings therein whereby outside air may enter the body without a drafty action. A pad rests on the bottom wall inwardly of the channel and upon which a baby may be disposed. A deflector is associated with this channel to direct the incoming air away from the baby, into the upper part of the cabinet body. A closure-like member is hinged to the top edge of the outer wall and its top edge is connected, by a flexible perforate material such as bobbine, to the top edge of an opening formed at the rear of the body. This member may be swung into an open or closed position and gusset-like pieces of foldable material connect the side edge of this member with parts of the wall.

The closure member mentioned, as well as the side walls and the top wall, are made of a transparent material which will permit the beneficial rays of the sun to pass therethrough. A plastic known as "vitaglass" well answers the purpose and it is not shatterable.

Associated with the inner ends of the side walls are upright imperforate panel-like parts in which are screened ventilation openings and on the inner face of each panel and associated with each opening is a turnable damper disc whereby the openings may be made effective or ineffective for their intended purpose.

Referring now in detail to that embodiment of the invention illustrated in the drawing, the improved solarium and airing cabinet includes an upright angle bar-like frame 10 of rectangular shape and defining an opening 11. A closure member 12 is hinged to the bottom of the open-

ing as at 13, whereby the closure member may be swung from a position closing said opening, as shown in Fig. 1, to a position uncovering said opening as shown in Fig. 2.

Centrally of the upper portion of the frame is a pivoted latch 14 whereby the member 12 may be detachably secured in the closed position. Flexible guy members 15 are secured to the frame at 16 and to the member 12 as at 17, which guy members support the closure member in a horizontal position, in which position it forms a table-like support upon which a baby may be placed for proper attention. For this reason, a cushion or pad 18 is attached upon that side of the member 12 which forms the upper side thereof when it is in its horizontal table-like support forming position.

If desired, but not absolutely necessary, I may provide on the other side of the member 12, a pair of laterally spaced folding legs 19. When the member 12 is in the closed position shown in Fig. 1, these legs fold in against said member. As said member 12 is swung outwardly and downwardly into horizontal position shown in Fig. 2, said legs swing relatively thereto into a vertical position and give additional support for the free margin of the said member.

Fixed to and projecting outwardly from the bottom end of the frame 10, is a horizontal frame 20 of angle bar-like material. This frame, which is rectangular in plan, receives the bottom end of an open front body for the cabinet 21. As said frame bears the weight of said body it is provided at the sides of its outer end with lateral extensions 22 to which one end of a guy chain 23 is attached, the other end of said chain being fixed to a part of the window casing in which the device is used. Each chain 23 is provided with a turnbuckle 24 (see Fig. 2) whereby the effective length of the respective chains may be accurately provided.

The body 21 includes a relatively low upright outer end wall 25 of opaque material and in said wall are air inlet openings 26 as best shown in Fig. 2. This end wall rises from an imperforate horizontal bottom wall 27 and inwardly of said wall 25 is a chamber or channel 28. In the horizontal top wall of this chamber are air outlet openings 29 whereby outside air, that has entered the channel 28 through the openings 26, may pass upwardly into the interior of the body 21. The front end of the bottom 27 is turned upwardly as a vertical flange 30 and which extends above the bottom of the opening 11 in the frame 10.

That part of the bottom between the channel 28 and the flange 30 supports a pad or cushion 31, upon which a baby may be placed. The front top edge of the channel 28 has a flap 32 hinged thereto as at 32a. This hinge is of the snap spring action type, similar to that employed in spectacle cases and snaps either to "opened" or "closed" positions. Thus it may be moved from the position shown in Fig. 1 wherein it deflects incoming air away from the baby on the pad to a position closing off the openings in the top wall of the channel.

An opening 33 is provided in the rear or outer end of the body above the wall 25. Associated with this opening is a closure 34 preferably made of material which permits the passage of the beneficial rays of the sun therethrough. This closure is hinged as at 35 (see Fig. 2) to the top edge of the wall 25, whereby it may be swung

from a position covering or closing said opening to a position uncovering said opening when more ventilation is desired for the interior of the cabinet.

5 To prevent the entrance of dust, insects and the like into the body of the cabinet when the closure is in the position shown in Fig. 2, I provide a foldable strip of open textile material 36 and fix one margin thereof to the top margin 10 of the closure 31 and the other margin to the inside of an angle bar 37 that defines the upper rear or outer corner of the body. Also, I affix 10 a gusset 38 of similar material to the end edges of the closure member 31 and to the inside of 15 upright rear end corner angle bars 39, as appears in Fig. 3. Of course, any suitable latch means (not shown) may be employed to detachably lock the closure 31 in the position covering the opening. With the arrangement described, insects 20 cannot enter the body when the member 31 is in the open position. Air entering the cabinet body through the opening 33 is deflected into the upper portion of the cabinet body so that no undesirable draft can affect the baby in the 25 cabinet body.

At the front end of the body is a top angle bar member 40 and side angle bar member 41. The bar 40 includes a vertical flange 42 and a horizontal flange 43. The bar 41 includes right angle flanges 44 and 45 respectively as shown in Fig. 3. The flanges 42 and 44 are adapted for engagement with one side of the frame 12 and defines an opening 46 that lines up with the opening 11 of the frame 10. The flanges 42 and 30 44 project inwardly beyond the opening and form a stop for the closure 12 of the frame. Preferably the flanges 42 and 44 are detachably 35 affixed to the frame by bolts 47. Thus in accommodating different size windows, the frame 10 is 40 made to fit a particular window opening and the cabinet body is then attached to the frame by the bolts 47.

In the flanges 45 of the bars are a plurality of 45 screen covered openings 48 (see Fig. 1) and on the inside of this flange there are pivoted damper plates 49, one for each opening 48. Each damper plate has an opening 50 therein. By turning the damper into one position, the opening 50 therein 50 may be brought to register with the associated opening 48 as appears in the two bottom dampers in Fig. 2 and by turning the damper into another position the damper closes the associated opening 48 as is evident from the top damper in Fig. 2. The screen may be of fine mesh so as to act as a 55 filter or separate air filter means may be provided in the openings, if desired.

The top wall 51 of the body of the cabinet is inclined downwardly and outwardly as a water shed and the front and rear ends extend under 60 and are fixed to the flange 43 and angle bar 37 respectively. The side margins of this top wall extend under an angle bar 52 as shown in Fig. 1 and which extends from the top front corner to the top rear corner of the cabinet body. The 65 side walls 53 of said body are disposed inside the flanges 45 and angle bars 37 respectively and the vertical flanges of the associated angle bars 52 and inside of strips 54 as appears in Fig. 1. The walls 53, 53 and 51 are made of the same material as the closure member 31.

To place one of the devices in a window opening, the outer guide strip 60 forming one side of an outer sash groove 61 in the uprights of a window frame is removed from the window frame 75 and the upper sash 62 is left in its normal posi-

tion and the lower sash 63 is raised in its groove 64 to an upper position. With the cabinet as a whole in its closed condition as shown in Fig. 1, the frame 10 is positioned in place with its bottom flange resting on the sill 65. Thereafter the strips 60 are replaced and the upper end of the guys 23 fixed to the sides of the window frame. By turning the turnbuckles 24 in said guys, the latter are properly adjusted. If necessary, the flanges at the sides of the frame may be further secured by suitable screws.

Thus the member 12 is disposed to the inside of the room of which the window forms a part and is readily accessible for opening and closing. When the member 12 is opened, the baby may be passed into the cabinet body and placed upon the pad 16. Also at this time the dampers 49 and the closure member 31 may be manipulated to provide the desired ventilation without drafts. When the member 12 is in the open position, it provides a table-like support disposed in the room and upon which the baby may be placed when giving it the attention it needs.

By the use of a folding awning 66 (see Fig. 2), which may be supported in conventional manner, it is possible to shade so much of the cabinet from the sun's rays except during such period as the child is to be given a sun bath.

By the use of the cabinet, a baby may be subjected to controlled sun bathing and airing and is amply protected from the adverse weather elements and from insects.

The various frame bars mentioned are preferably secured together in operative relation by screws or bolts so that after the cabinet body 21 is removed from the frame 10, it may be taken apart and arranged as a package convenient for storage in a small space.

While I have referred in detail to the form arrangement and construction of the parts involved, the same is to be considered only in the illustrative sense so that I do not wish to be limited thereto except as may be specifically set forth in the appended claims.

I claim as my invention:

1. A device of the kind described embodying therein a cabinet body having an opening at its inner end and an opening at its outer end and including top, bottom and side walls, the top and side walls including parts made of material for the passage of beneficial rays of the sun therethrough, means providing a channel within and along the outer bottom corner of the cabinet body and having an air inlet opening and upwardly facing air outlet openings therein, a closure hinged to a part of said channel providing means for covering and uncovering said opening in the outer end of the body, and foldable means between the top and side margins of said closure and parts of the cabinet body defining the opening at the outer end of the body, and means to which the inner end of the cabinet body is attached, said means being adapted to be secured in a window opening and including a doored opening for communication with the opening at the inner end of the cabinet body.

2. A device of the kind described embodying therein a cabinet body having an opening at its inner end and an opening at its outer end and including top, bottom and side walls, the top and side walls including parts made of material for the passage of beneficial rays of the sun therethrough, means providing a channel within and along the outer bottom corner of the cabinet body and having an air inlet opening and upwardly

facing air outlet openings therein, a member having a hinged connection with a part of said channel providing means, and movable into a position closing said upwardly facing air outlet openings to a position for deflecting the air passing through said openings into the upper portion of the cabinet body, a closure hinged to a part of said channel providing means for covering and uncovering the opening at the outer end of the body, and means to which the inner end of the cabinet body is attached, said means being adapted to be secured in a window opening and including a doored opening for communication with the opening at the inner end of the cabinet body.

3. A device of the kind described embodying therein a cabinet body having an opening at the inner end and an opening at its outer end and including top, bottom and side walls, parts of the top and side walls being made of material for the passage of beneficial rays of the sun therethrough, other parts of certain of said side walls having openings therein and carrying parts whereby said openings may be opened or closed, means providing a channel along the outer bottom corner of the cabinet body and having air inlet openings and upwardly facing air outlet openings therein, a member having a hinged connection with a part of the channel providing means and movable into a position closing said upwardly facing air outlet openings for deflecting the air passing through said openings into the upper part of the cabinet body, there being air inlet openings in other parts of said side walls, means for opening and closing said openings, and means to which the inner end of the cabinet body is attached, said means being adapted to be secured in a window opening and including a doored opening for communication with the opening at the inner end of the cabinet body.

4. A device of the kind described embodying therein a cabinet body having an opening at its inner end and an opening at its outer end and including top, bottom and side walls, the top and side walls including parts made of material for the passage of beneficial rays of the sun therethrough, means providing a channel within and along the outer bottom corner of the cabinet body and having an inlet opening and upwardly facing air outlet openings therein, a closure hinged to a part of said channel providing means for covering and uncovering said opening in the outer end of the body, upright means adapted to be disposed in a window opening and to which the inner end of said body is attached, said means having an opening therein in communication with the opening in the inner end of the cabinet body, a door hinged to said means at the bottom of the opening therein, and which door, when in a position uncovering said opening, being in a substantially horizontal position to provide a table-like support.

5. A device of the kind described embodying therein an upright member adapted to be disposed in a window opening and having an opening therein, a door for covering and uncovering said opening, a cabinet body having an open inner end defined at least in part by an inturned flange which is adapted for engagement with said member, means for securing said flange to said one side of said member, the cabinet body including a bottom, side, top and outer end walls, the outer end wall being formed to define an opening therein, said top and side walls being

made of material that permits the passage of the beneficial rays of the sun therethrough, a member mounted on the outer wall part below the associated opening and operable to open and close the same, means in part of said side walls providing air inlet openings therethrough, dampers, one associated with each of said openings for opening and closing the same, a channel

5 within and adjacent said outer end wall and having air inlet and outlet openings therein, and a member mounted on said channel providing means and movable to either open the same and form a deflection for the incoming air, or for closing the same.

MAUD E. TRONE.
